UNITED STATES PATENT OFFICE

EDWARD N. JACOBI, OF MILWAUKEE, WISCONSIN, ASSIGNOR TO BRIGGS AND STRATTON CORPORATION, OF MILWAUKEE, WISCONSIN, A CORPORATION OF DELAWARE

HANDLE ASSEMBLY

Application filed July 16, 1928. Serial No. 292,962.

This invention relates to certain new and useful improvements in handle assemblies and has as an object the provision of improved and simplified means for mounting handles especially designed for the operation of automotive window regulators and door locks.

Another object of this invention resides in the provision of improved means contained within the handle shaft and cooperating with the handle when placed thereon to secure the handle on the shaft against detachment.

And a still further object of this invention resides in the provision of an improved handle assembly in which a spring detent is contained within the handle shaft for engagement with the handle as it is moved thereover to thus firmly secure the handle on the shaft and, at the same time, permit its ready removal for the purpose of replacements or repair.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated two complete examples of the physical embodiment of my invention constructed according to the best modes I have so far devised for the practical application of the principles thereof, and in which:

Figure 1 is a view, partly in side elevation and partly in section, of a window handle assembly embodying my invention;

Figure 2 is an enlarged, sectional view taken transversely through Figure 1 on the plane of the line 2-2; and

Figure 3 is a fragmentary, detail view similar to Figure 1 and illustrating a slightly modified structure.

Referring now more particularly to the accompanying drawing, in which like numerals designate like parts throughout the several views, 5 designates a shaft which is

preferably of irregular shape in transverse section and connected with the mechanism to be operated such as a window regulator, door latch or the like, and 6 a handle or lever member having a lateral boss 7 on one end which is bored at 8 to conform with the shaft 5, the outer end of which is received therein. The handle 7 may be provided with an operating knob 9 at its outer free end and the fit of the handle bore 8 and the shaft 5 assures the rotation of the shaft with the handle.

The boss 7 has one or more apertures 10 adapted to be registered with a transverse bore or recess 11 in the shaft, the bore 11 being preferably of greater diameter than bore 10 and having a two-diameter spring pressed plunger 12 slidably therein. The plunger is confined within its bore 11 for limited movement by a flange or shoulder 13 wedged inwardly at the outer end of the bore 11 to cooperate with the shoulder 14 formed at the juncture of the two diameters of the plunger, a spring 15 confined between the closed end 16 of the bore 11 and the inner end of the plunger at all times yieldably urging the outer end of the plunger, which is the end of smaller diameter, beyond the shaft periphery.

The outer end of the plunger is preferably tapered, as at 17, to facilitate its engagement in the registered aperture 10. To assemble the handle on the shaft 5, the plunger is depressed against the spring 15 and the handle engaged over the shaft with the aperture 10 that gives the desired position of the handle on the shaft in register with the plunger. As the aperture 10 registers with the plunger, it is moved thereinto by its spring 15 and the handle firmly fixed on the shaft. When it is desired to remove the handle for the purpose of repair or replacement, a suitable tool is engaged in the aperture 10 in which the plunger is positioned to depress the same against a spring, as will be readily apparent.

In the embodiment illustrated in Figure 3, the plunger 12 is replaced by a spring 18 of approximately hair-pin shape confined within a milled slot 19 in the shaft and having one end 20 directed laterally through an aperture

21 registering with the milled slot so that its end 20 engages in the bore 10 of the handle as the same registers therewith.

From the foregoing description, taken in connection with the accompanying drawing, it will be readily apparent to those skilled in the art to which an invention of the character described appertains, that I have provided a novel and improved means for readily securing a handle member upon a shaft against detachment which means is contained within the shaft and cooperates with the handle as it is engaged thereover to firmly lock the same thereon.

15 What I claim as my invention is:

1. In a device of the character described, a lever member having a bore, a shaft, one end of said shaft being longitudinally slotted and provided with a transverse aperture communicating with the slot, said shaft end being engageable in the lever member bore, a substantially hair-pin shaped spring confined within the shaft slot, and a laterally directed part carried by the spring and yieldably projected through said transverse aperture beyond the shaft to engage in an aperture in the wall of the lever member bore when said shaft end is engaged therein, the projection of the laterally directed part through said transverse aperture and into the lever member aperture securing the spring in the longitudinal slot and the shaft in the lever member bore.

2. In a device of the character described, a lever member having a bore, a shaft, one end of said shaft being longitudinally slotted and provided with a transverse aperture communicating with the slot and being engageable in the lever member bore, a substantially hairpin shaped spring confined within the shaft slot with one leg engaging the wall of the lever member bore to yieldably urge its other end towards the transverse aperture, and a laterally directed part on said other leg projected through the transverse aperture beyond the shaft to engage a recess in the wall of the lever member bore, the projection of the laterally directed part through said transverse aperture and into engagement with the lever member carried recess securing the spring in the longitudinal slot and the shaft in the lever member bore.

3. In a device of the character described, a lever member having a bore, a shaft having a longitudinal groove at one end with an opening communicating with the bottom of the groove and engageable in the lever member bore, the wall of the bore closing the open side of the groove, a spring bent medially upon itself and received in said longitudinal groove with one end engaging the wall of the bore to yieldably urge its other end toward the bottom of the groove, and a laterally directed part on said other end of the spring projectable through the opening be-

yond the shaft to engage in a recess communicating with the bore of the lever member, the projection of the laterally directed part through the shaft opening securing the spring in the groove and the shaft in the lever member bore.

In testimony whereof I have hereunto affixed my signature.

EDWARD N. JACOBI.
